UNITED STATES PATENT OFFICE.

JOSEPH N. PROVENZANO, OF NEW YORK, N. Y.

DESIGN FOR A KNOB OR HANDLE FOR CANES.

SPECIFICATION forming part of Design No. 16,502, dated February 2, 1866.

Application filed August 18, 1885. Serial No. 174,751. Term of patent 7 years.

To all whom it may concern:

Be it known that I, JOSEPH N. PROVENZANO, a subject of the King of Italy, residing in the city, county, and State of New York, have 5 invented and produced a new and original Design for Knobs or Handles for Canes, of which the following is a specification, reference being had to the accompanying drawing, forming part thereof.

10 The said drawing represents an isometrical perspective of my new design for cane heads or handles.

I am aware that heretofore medallions have been worked into or upon various articles of 15 manufacture, such as clocks, vases, table-ware, &c.; and I do not seek to cover such means of ornamentation, broadly.

The novelty in my case consists in the special design for cane heads or handles herein 20 shown and described, in which a certain ornamentation representing a medallion or antique coin is formed upon the top of the head, while the barrel or cylindrical portion is formed with certain other ornamentation representing me- 25 dallions or antique coins of a smaller size than that first named.

The knob A consists of the body or barrel a and the top or head a'. The latter is formed and ornamented with the representation of a comparatively large medallion or antique coin, 30 C. The barrel a is formed with a series of smaller ornamentations, also representing medallions or antique coins, the whole constituting a novel design of neat and uniform appearance, which is unique, interesting, and 35 instructive.

I claim—

The design for cane heads or handles herein shown and described, the same consisting of the ornamentation representing a medallion or 40 antique coin formed upon the top a', and of the ornamentation representing a series of smaller medallions or antique coins formed upon the body or barrel a of the said cane handle or head A.

JOSEPH N. PROVENZANO.
